ABSTRACT

A hinge means for use with glass doors having solid frames includes a hinge element for a pivotal hinge of the type used where the door is pivoted at top and bottom, which element is laterally adjustable to provide means for correcting misalignment after the door has been hung.

COMBINED HINGE AND GLASS DOOR UNIT

CROSS REFERENCE TO RELATED APPLICATION

This application is a continuation-in-part of my prior copending application Ser. No. 820,541, Filed Apr. 30, 1969, now U.S. Pat. No. 3,555,733 issued Jan. 19, 1971, Entitled, Combined Hinge and Glass Door Unit, and discloses and claims in part the subject matter disclosed and claimed in that application.

BACKGROUND OF THE INVENTION

This invention relates to hinges and in particular to a novel hinge means for use with frame elements on glass doors.

In the prior art, glass doors of the type used in commercial establishments having a metal frame including a top and bottom shoe, were hung by means of pivot-type hinges connected to the top and bottom shoes. The advantages of my new combined hinge and door means over the prior art were fully set forth in my prior copending application referred to above.

While my prior application represents an improvement over the art, I have noted that it is desirable to provide for lateral adjustment of the door at both the top and bottom pivot points after the door has been hung in place.

SUMMARY OF THE INVENTION

The present invention provides a means for pivotally mounting a glass door which includes solid frame members and for laterally adjusting the position of the door with respect to its pivots after the door has been hung. It comprises means externally engaging the frame portion of the door and bearing against it, which provide a means for laterally adjusting the door with respect to the fixed pivot upon which the door is mounted.

Accordingly, it is an object of this invention to provide a novel hinge means which is adjustable to compensate for lateral misalignment after the door is hung, and adaptable for use with existing hinge elements.

It is a further object to provide such a hinge means which is particularly adaptable to pivotal hinges of the type used on swinging doors having solid frame members.

These and other objects of the invention will become apparent from the following description with reference to the bottom,

BRIEF DESCRIPTION OF THE DRAWINGS

FIG. 1 is a front view of a pivotally mounted door having hinge means at the top and bottom shown in a suitable environment;

FIG. 2 is an enlarged view taken as indicated by the lines and arrows 2-2 in FIG. 1; and

FIG. 3 is an enlarged view taken as indicated by the lines and arrows 3-3 in FIG. 1.

DESCRIPTION OF PREFERRED EMBODIMENTS

Although specific forms of the invention have been selected for illustration in the drawings, and the following description is drawn in specific terms for purpose of describing these forms of the invention, this description is not intended to limit the scope of the invention which is defined in the appended claims.

Referring to the FIGS., FIG. 1 shows a door designated generally 10 which includes a glass panel 11 and a metal frame including a top shoe 12 and a bottom shoe 14. The door is supported by pivot type hinges attached to the top and bottom shoes and the supporting frame and door structure.

The upper hinge 16 is more clearly shown in FIG. 3 and comprises a generally box-like rectangular housing 18 which has a peripheral groove about three sides so that it fits snuggly into a rectangular notch in the shoe 12, overlapping and engaging the sides of the shoe with its supporting flanges 20.

The housing 18 contains a central bore which has press fitted therein a bushing 24 forming a bearing for the pintle 26. The pintle is normally retained in the structure surrounding the door by any suitable means well known in the art and provides the means whereby the upper portion of the door is retained and pivoted.

The housing and bearing remain fixedly engaged to the pintle 26 while the frame and glass portion of the door is movable with respect to the housing.

To shift the door 10 FIG. 1 to the left or right, I have provided a novel hinge means which, in this embodiment, comprises a plurality of balls disposed in angled slots on both sides of the housing 18 and actuated by set screws threaded through a portion of the housing 18 and actuated by set screws threaded through a portion of the housing 18 to engage the balls and drive them in the slots against the adjoining door. The balls 28 and 30 in FIG. 3 are preferably steel and are disposed in a close sliding fit in the angled slots 32, 34 respectively. These slots are most preferably on an angle of between 30 and 45 degrees. Holes 36, 38 are drilled and tapped to receive set screws 40 and 42 respectively in threaded engagement. The lead ends of the set screws are rounded as shown in FIG. 3.

The housing 18 is positioned in a clearance slot in the upper shoe of the frame of the door. In the position shown in FIG. 3, this clearance slot provides a clearance on both sides of the housing; the clearance being designated 44 on the right and 46 on the left.

It will be apparent from what has been described thus far that if it is desired to shift the door with respect to the pivot or pintle 26 after it has been hung, the screws 40 and 42 can be advanced or retracted in order to actuate the balls 28 and 30 and either cause them to be advanced from their respective slots against the frame of the door or allow them to be forced into the housing 18. Thus, for example, if it is desired to shift the door to the left when viewed in FIGS. 1 and 3, one would withdraw the screw 40 slightly and advance the screw 42 against the ball 30. As the advancement continued, the door would shift to the left and the ball 28 would ultimately come to rest against the screw 40.

The hinge just described provides for lateral adjustment of the door with respect to the upper pintle. The bottom hinge means provides rotative adjustment as well as lateral adjustment. The bottom shoe 14 has attached to it a hinge designated generally 50, FIG. 1, which supports the door and provides a means about which it pivots. This hinge is shown in more detail in FIG. 2 and in my prior copending application referred to above. One element of the hinge comprises a floor mounted pintle 52, FIG. 2 which is a standard item well known in the art. This pintle is mounted to a plate fixed

in the floor and can be rotated with the door. The pintle is generally rectangular in cross section and the sides are beveled inwardly toward the upper end to accept the mating hinge member (as described in my prior copending application). My invention insofar as this hinge means is concerned lies in the remaining elements of the hinge in combination with my new door, as I shall now describe in more detail.

The elements of the hinge which are attached to the door include a housing 54 which has a peripheral slot about three sides thereof so that the side walls form extending flanges 56 (approximately one-half of an inch thick) to engage and overlap the sides of the bottom shoe 14. The slot in the embodiment illustrated in the drawings is on the order of three-fourths of an inch wide, as is the shoe 14. Thus the housing 54 is designed to fit snuggly against the sides of the shoe 14, embracing it in a sliding fit. The housing is seated in the notch in the shoe 14 so that its bottom surface is in the same plane as the bottom of the shoe 14.

The shoe 14 is solid around the periphery or base portion thereof and, as described in my copending application, has a channel means formed above the base on the inner side thereof for reception of the glass panel 11. The frame, of which the shoe is a part, is attached to and coacts with the panel 11 so that the hole forms a unitary structure, and accordingly, a load imparted to the face of the glass panel 11 in order to open it will be distributed through the frame member 14.

The inner sides 60 and 62 of the housing formed by the peripheral groove are spaced from the side walls 64 and 66 respectively of the notch in the shoe 14 to provide a clearance for lateral adjustment. Such adjustment is made by the balls 68, 70 which are in sliding engagement with the housing in the angled holes in the housing, and are actuated by set screws 72 and 74 respectively to make up the clearance space. The housing then can be adjusted laterally and made to fit snuggly with the heads of the set screws bearing against the balls 68 and 70 which in turn bear against the shoe 14. By extending and retracting the set screws in the manner previously described the frame and glass portions of the door can be shifted laterally with respect to the pintle 52.

The housing 54 has a blind bore which accepts a cap element 82. The cap is substantially cylindrical and the top of the cap rests against the blind end of the bore while the sides of the cap rotatably engage the sides of the bore. The cap has a centrally located blind hole disposed axially therein and having sloping sides to accommodate the upper end of the pintle 52.

The cap 82 has an ear 84 extending from one side into a clearance slot 86 which extends from one side of the bore in the housing. On either side of the housing, set screws 90, 92 are threaded through the walls to engage the ear 84. By advancing one set screw (90, 92) relatively more than the other, the housing can be rotated about the cap 82. By tightening both set screws (90, 92) against the ear 84, the housing can be fixed in position with respect to the cap.

Thus, my invention provides a means for engaging a standard pintle and rotating therewith, which means can be fixedly connected to a solid shoe to pivot a door; said means providing for the relative adjustment of said door with respect to said pintle after the door is hung.

In operation, the housings 18 and 54 are placed in the notches in the shoes 12 and 14 respectively. If the door does not hang correctly or close properly against the jam, rotational adjustment is possible by means of backing off one of the set screws 90, 92 and advancing the other, and lateral adjustment is possible by relative adjustment of the set screws 72, 74, and 40, 42.

It will be understood that various changes in the details, materials and arrangement of parts which have been herein described and illustrated in order to explain the nature of this invention, may be made by those skilled in the art within the principal and scope of the invention as expressed in the following claims.

It will further be understood that the "Abstract of the Disclosure" set forth above is intended to provide a non-legal technical statement of the contents of the disclosure in compliance with the Rules of Practice of the United States Patent Office, and is not intended to limit the scope of the invention described and claimed herein.

What is claimed is:

1. A hinge means for use with the frame portion of a door and mating rotatable pintle element, comprising:
  - a. Means for engaging said pintle for rotation therewith;
  - b. Housing means rotatably engaging said last mentioned means, and overlapping and engaging said frame;
  - c. Adjustment means engaging said housing means and said frame for laterally adjusting the position of said frame with respect to said pintle while the door is in its hung condition.
2. The invention of claim 1 wherein said first mentioned means includes a substantially cylindrical cap having an axial hole therein for receiving said pintle.
3. The invention of claim 1 wherein said housing includes a plurality of flanges extending therefrom, said flanges overlapping and being in sliding engagement with said frame.
4. The invention of claim 1 wherein said adjustment means includes a plurality of screws threaded through said housing to contact a plurality of movable elements engaging said frame.
5. The invention of claim 4 wherein said movable elements comprise a plurality of balls in sliding engagements in a plurality of holes in said housing.
6. The invention of claim 5 wherein said housing means includes a body having a peripheral groove about a portion thereof, said groove forming flanges for engaging said frame in a snug fit; and plurality of screws are provided in threaded engagement with said housing means to engage said balls, said balls entering in said peripheral groove to extend therein to contact said frame and fix the lateral position of said frame with respect to said pintle.
7. The invention of claim 2 wherein said cap includes an ear extending from one side thereof and said housing includes a body having a substantially cylindrical hole therein for receiving said cap in sliding engagement with the cylindrical portion thereof and a clearance slot for reception of said ear, said ear being spaced from said body within said slot, and a plurality of screws are disposed to pass in threaded engagement through the walls of said body to contact said ear, said screws and said ear providing rotational adjustment means for said door with respect to said pintle.

8. The invention of claim 1 wherein said housing means coacts with said frame to transmit the rotational force load required to rotate the door about the pintle.

9. A combined hinge and door unit, comprising a door including a panel and a plurality of frame members coacting with said panel to form a unitary structure, and a pivotal hinge means for engaging an external pintle for pivotal movement therewith; said hinge means comprising a housing means rotatably engaging said pintle and lateral adjustment means engaging said frame and said housing means for laterally adjusting the position of said frame with respect to said pintle while said door is in its hung condition.

10. The invention of claim 9 wherein said housing means includes a body having a peripheral groove about a portion thereof, said groove forming flanges overlapping and engaging said frame in a snug fit and coacting therewith to transmit the rotational force necessary to pivot said unit about said pintle; and said adjustment means includes a plurality of screws threaded through said housing to contact a plurality of movable elements engaging said frame.

11. The invention of claim 10 wherein said movable elements comprise a plurality of balls in sliding engagement with a plurality of holes in said housing.

12. The invention of claim 11 wherein said holes are disposed on an angle with respect to the path of lateral movement of said doors.

13. The invention of claim 11 wherein said balls enter into said peripheral groove to extend therein to contact said frame.

14. The invention of claim 1 wherein said adjustment means comprises a plurality of engagement means and a plurality of actuating means; said engagement means being movably mounted within said housing means to extend therefrom; said actuating means engaging said engagement means to position said engagement means with respect to said housing means.

15. The invention of claim 14 wherein said engagement means comprises a plurality of balls.

16. The invention of claim 15 wherein said balls are positioned in angled holes within said housing means.

17. The invention of claim 14 wherein said engagement means is freely movable within said housing means.

18. The invention of claim 14 wherein said actuating means is adjustable from without said housing means when said door is in its hung condition.
